UNITED STATES PATENT OFFICE.

JAMES WEBB SAFFOLD, OF CLEVELAND, OHIO

BOOT OR SHOE.

1,219,165.

Specification of Letters Patent. Patented Mar. 13, 1917.

Application filed October 24, 1914. Serial No. 868,398.

To all whom it may concern:

Be it known that I, JAMES WEBB SAFFOLD, a citizen of the United States of America, residing at Cleveland, in the county of 5 Cuyahoga and State of Ohio, have invented certain new and useful Improvements in Boots or Shoes, of which the following is a specification.

My invention relates to improvements in 10 boots or shoes, and has for its object the provision of a sole brace or support, preferably secured in position within the shank of the shoe, which will yieldingly stay the foot of the wearer, lending resilient support 15 thereto, and which will retain the shoe in its normal shape and thereby prolong its life, as well as causing the wear of the sole to be more even.

In numerous prior boots and shoes it has 20 been common practice to insert metallic stiffeners, or springs of different types, but I have found after long experiment that none of these was most efficiently applied and properly shaped to attain the above 25 advantages. It has been common practice to fasten one or both ends of such stiffeners or springs, or otherwise securely anchor them in the shoe structure, so that the best action thereof is impeded.

29 A shoe containing my improvements is made in the usual manner, but affords a special construction throughout the shank, which contains a properly arched and shaped spring steel plate, free at its ends 35 but anchored generally in position, preferably by riveting it interiorly of, and centrally to the insole. This resilient steel member forms an arch of light weight and proper curvature and is forwardly broadened with a bearing surface sliding upon the top side of the sole, while a corresponding support is rearwardly provided by a longer and narrower portion sliding upon the top side of the sole immediately above 40 the heel. In this way the sole brace is free to give at both ends, while it is maintained in its proper relative position with respect both to the shoe and the foot of the wearer during use, by being built permanently into 45 the shoe structure.

Further details of my improvements may be explained in connection with the accompanying drawings, wherein:

50 Figure 1 is a diagrammatic view in exaggerated cross-section, illustrating the support and action of the sole brace during use.

Fig. 2 is a plan view of one of said sole braces, illustrating its resilient action by dotted lines and the reduction in weight by cutting away the central portions thereof. 65

Fig. 3 illustrates the completed shoe equipped with my improved sole brace in side elevation, partially broken away and in section, and Fig. 4 is an underside plan view of the insole with an attached sole brace, 65 riveted centrally throughout its body portion.

I have employed the same character of reference in the several figures of the drawings to indicate the similar parts. 70

The shoe of Fig. 3 is made in the usual manner, except the shank construction containing my improvement. Between the sole *a* and the insole *b* of said shoe, there is provided an arched steel member *c*, whose outline is best shown in Fig. 4. The rear portion *c'* of said member, is somewhat elongated and is cut away at the sides, so that the nails of the heel will not strike or interfere therewith. Forwardly, the member *c* is 80 expanded or widened laterally and transversely bent to afford a wide bearing section *c''* for the top side of the sole. Oval rivets *d* interiorly secure said member *c* in position beneath the insole *b*, thereby leaving it free 85 to flex sufficiently with the foot of the wearer to afford a distinctly resilient support for the arch of the foot.

This construction, it will be seen, permits both ends of the sole brace, a slight elongating movement without any tendency to buckle the insole or spring the shoe out of shape. 90

It is apparent that these results would not be attained were the ends of the supporting member unchored, while a rigid metallic member presents the objections of being too heavy, and failing to conform to the arch of the wearer's foot because of its unyielding character. 95

The distinctive features of my improvement may receive further explanation in connection with the first two figures of the drawings, in Fig. 1 of which I have shown in exaggerated form, the action of the sole brace during use. Said sole brace *c* is assumed to be stationary within the shoe along the median line *e--e*, its curvature being considerably more than would be found with any normal foot. The supporting 105 heel *h* carries the rear extremity *c'* of said sole brace, while the widened forward ex-

tremity *c*'' rests upon the base line. In walking, the weight of the wearer is generally applied throughout the length of the arch as indicated by the successive sets of darts *f*, and in the directions shown. This will elongate the sole brace at the moment of extreme depression, so that it assumes the position of the dotted line *g*, but it immediately regains its arched shape upon the

removal of the wearer's weight therefrom.

In Fig. 2 this elongation also is indicated by dotted line *g*, while the oval rivet and rivet hole are well shown therein. The central cut away portions *c*³ and *c*⁴ permit a much lighter construction, while affording a wide bearing surface for the sole brace. The oval rivet holes do not materially weaken the sole brace at the critical anchoring or shank portion thereof.

Having now described the preferred embodiment of my invention, I claim as new, and desire to secure by Letters Patent, the following:

1. A boot or shoe having a resilient arched steel member centrally secured to the insole permanently built into the shank thereof, said member having an extended rear end supported in position to slide upon the heel section and a widened forwardly disposed supporting section, free likewise to slide upon the upper face of the sole, beyond the arch, substantially as set forth.

2. A boot or shoe equipped with a resilient arched sole brace interiorly secured in position within the shoe permanently built into the shank thereof and having an extended rear supporting section and a widened front supporting section, both of which are free to move as the resilient sole brace is elongated by pressure or weight thereon, substantially as set forth.

3. A boot or shoe having an arched sole

brace secured approximately at its middle portion only with its ends left free to slide; said sole brace being centrally cut away in its body portions to reduce the weight thereof, rearwardly elongated and narrowed to afford a bearing surface above the heel and forwardly widened to afford a bearing surface upon the sole of the shoe beyond the arch, substantially as set forth.

4. A boot or shoe having built into its shank, an arched resilient sole brace centrally secured to the shoe structure with its ends respectively bearing upon and left free to slide above the heel and forwardly of the arch upon the sole of the shoe, substantially as set forth.

5. A boot or shoe equipped with a resilient arched sole brace; the same having an integral anchoring portion intermediate of its ends and angularly bent unattached supporting ends, with a median portion of said sole brace cut away adjacent to the wider section thereof, substantially as set forth.

6. A sole-brace, comprising an insole adapted to be fixed in position within a boot or shoe, an arched spring-steel plate attached to the underside thereof, comprising an elongated rear or heel-bearing portion, a widened forwardly positioned sole-bearing portion, and a connecting intermediate portion laterally cut away and perforated centrally, and a rivet of oval cross-section, passing through said perforation and centrally securing the arched member to the insole, substantially as set forth.

In testimony whereof I do now affix my signature in the presence of two witnesses.

JAMES WEBB SAFFOLD
